MECHANISM FOR FEEDING BUTTONS TO
SEWING MACHINES

Dewey L. Conner, Grand Rapids, Mich.

Application October 31, 1932, Serial No. 640,377

24 Claims. (Cl. 112—113)

The present invention relates to mechanism for feeding buttons to operatively-registering position with the needle of a sewing machine; and its object is, generally, to provide improved mechanism of that character; and more particularly, to provide such mechanism whereby each of the buttons may be thus fed to different registering positions with the needle; and further, to provide feeding mechanism operable by the driving means of said machine; and further, to provide in such a mechanism improved combined and cooperating parts for effecting these objects; and further, to provide an improved button-carrying strip for feeding the buttons; and further, to provide improved means for detaching the buttons from said strip; and further, to provide in combination with such feeding mechanism improved means for severing said strip.

These and any other objects hereinafter appearing are attained by, and the invention finds preferable embodiment in, the illustrative mechanism particularly described in the body of this specification and illustrated by the accompanying drawings, in which:

Figure 1 is a right-hand-side elevational view of a sewing machine with a button-feeding mechanism;

Figure 2 is a plan view of parts of said mechanism, partially sectioned horizontally on line 2—2 of Figure 3;

Figure 3 is a right-hand-side elevational view of parts of said machine and said mechanism, partially sectioned vertically on line 3—3 of Figure 2;

Figure 4 is a horizontal sectional view of parts of said mechanism taken on line 4—4 of Figure 3;

Figure 5 is a left-hand-side elevational view of said machine and mechanism;

Figure 6 is a front elevational view thereof;

Figure 7 is a front elevational view of the same, certain parts being vertically sectioned on line 7—7 of Figures 1 and 5;

Figure 8 is a plan view of a feed strip with buttons attached thereto;

Figure 9 is an edgewise view thereof, partially sectioned on line 9—9 of Figure 8;

Figure 10 is a longitudinal central vertical sectional view thereof in another position and of means for detaching the buttons from the strip;

Figure 11 is a vertical sectional view thereof and of adjacent parts taken on line 11—11 of Figure 10;

Figure 12 is a plan view of said means, sectioned on line 12—12 of Figure 10;

Figure 13 is a plan view (enlarged) of a por-

tion of the button-carrying strip and feeding means therefor;

Figure 14 is a transverse sectional view thereof taken on line 14—14 of Figure 13;

Figure 15 is a transverse sectional view of the same taken on line 15—15 of Figure 13 (the strip 17 being omitted in this view);

Figure 16 is an elevational view (enlarged) of adjusting devices indicated at the right-hand side of Figures 6 and 7;

Figure 17 is a sectional view thereof taken on line 17—17 of Figure 16;

Figure 18 is a sectional view of certain parts taken on line 18—18 of Figure 5;

Figure 19 is an elevational view of an operating pedal;

Figure 20 is a view in perspective of a cam wheel and detent;

Figure 21 is a side view of said wheel;

Figure 22 is a sectional view of certain parts taken on line 22—22 of Figures 5 and 6;

Figure 23 is a side view of a cam wheel;

Figure 24 is a sectional view of certain parts taken on line 24—24 of Figure 1;

Figure 25 is a sectional view of certain parts taken on line 25—25 of Figure 7;

Figure 26 is a top plan view of certain parts shown in Figure 13 illustrating a somewhat modified construction thereof.

In the embodiment of the invention illustrated by these drawings, a sewing machine is shown

having mechanism for feeding buttons into position to be sewed on garments, etc. This sewing machine, of any form or type suitable for this purpose, has a frame 1, table 2, arm 3 overhanging the table, shaft 4 with pulleys 5, 6 carrying the driving belt 7, needle 8 carried by vertically-reciprocating needle bar 9, pressure feet 10 carried by links 11 on the foot-raising bar 12, shuttle-operating rod 13, thread-guiding and tensioning devices 14, 15, etc. as indicated in the various views.

Flat buttons 16 are fed along the sewing machine's table, over the work piece or fabric sheet on which they are to be sewed, in the following manner and by the following mechanism:

A thin strip 17 of suitable material, as sheet metal, has struck-out tongues 18 thrust through the buttons' holes 19 and bent on the buttons sufficiently to attach the same in spaced relation on the under side of the strip as shown. Said tongues are sufficiently rigid to normally hold

the buttons on the strip as seen in Figure 9, and at the same time are sufficiently pliable to be bent as shown in Figures 10 and 3 into position

releasing the buttons; and the strip is sufficiently pliable to be curved into shapes seen in Figures 1, 3, 5, 6 and 10. This strip is moved to advance the buttons one at a time to sewing position under the needle, and after each button is sewed through one pair of its holes it is automatically advanced a sufficient distance to be sewed through a second pair of its holes.

A pair of parallel arms 55 at the opposite sides 10 of the machine's frame are swingably mounted thereon at 56. The free upper ends of these arms carry a horizontal pivot rod 57 extending transversely of the machine above its table 2. A pair of laterally-spaced bars 58 turnably and slidably mounted on this pivot rod extend toward the front of the machine. Chains 20 are carried by spaced wheels 22 and 21, journaled at 30 on these bars respectively and are composed of links 23 connected by links 25. The links 23 are 15 composed of thin upper and lower plates 44 projecting laterally beyond the links 25 and having bevelled corners 24. The lower plates 44 are provided at the bevelled corners with angularly disposed flanges 24^a extending upwardly at an inclination and forming abutting surfaces located 20 between the upper and lower plates 44 for engaging the button 16 at opposite sides thereof. The button engaging flanges 24^a of the proximate ends of the adjacent links 23 are spaced 25 apart to receive a portion of the buttons 16 between them. Any other suitable means may, of course, be employed for forming the button engaging surfaces.

To feed the buttons successively, the strip 17 30 with the buttons attached thereto is moved by suitable means as the pedal 33 (as hereinafter described) toward the left-hand side of Figures 1 and 2 and toward the needle 8 by the travel of the chains 20 whose links 23 engage the buttons at their diametrically opposite edges. The chains are thus travelled by their wheels 21 rotated step by step by coaxial arms 26 having pawls 27 pivoted thereon at 60 and engaging the teeth 28 of the ratchet wheels 29 on the vertical shafts 30 of said wheels 21. These arms 26 are turned by the rods 31 pivoted to the opposite extensions 32 of arms 26 and moved by suitable means as by the pedal 33 whose rod 34 is pivotally connected at 16 with the slide bar 15 whose slot 106 contains the lateral pin 105 of one arm 35 of a bell crank lever whose other arm 36 is connected to a rod 37 having a cross bar 38 on which the rods 31 are pivoted.

When the strip 17 has been thus moved toward the needle to a certain position (best seen in Figures 3 and 10), the buttons are, one at a time, detached from the strip by means shown in said views. Such means includes a foot member 39 in the path of, and above, the moving strip 17 (best seen in Figures 10, 11 and 12) comprising a pair of laterally spaced parallel parts 40 having upper surfaces 41 curving upwardly (as seen in Figure 10) from their front edges or toes 42, and side portions 43. In the strip's fed movement, 50 these toes engage under the strip and over the buttons, so that the strip slides on the surfaces 41 and is curved upwardly from the buttons thereby bending the tongues 18 downwardly and out of the buttons' holes to detach the buttons from the moving strip. The curved portion of the strip from which the buttons have been thus detached passes upwardly and rearwardly on the member 39, as shown in Figures 1, 3 and 5, to be discarded, while the detached buttons are fed by the links 23 forwardly, into position to be sewed on the fabric

work piece by the needle which passes alternately through a pair of the button's holes, the needle's carrying bar 9 being mounted for oscillating movement sidewise of the machine as herein-after explained.

In this fed movement of the strip 17 and of the buttons detached therefrom, they are guided by the thin top and bottom plates 44 of the links 23 which engage the buttons on their upper and lower sides, said top plates engaging under the strip as shown in Figures 13 and 14.

In order to position the button-engaging portions of the two chains 20 so that the strip 17 will be guided in a direct line to the needle, the outer edges 45 of the plates 44 of such portion of one of the chains slide on a bearing member 46 adjustable relatively to such direct line by its threaded rods 47 having setting nuts 48 engaging the upwardly extending rib 49; and the outer edges 50 of the links 25 of such portion of the other chain slide on the bearing member 46¹ adjustable relatively to such direct line by its threaded rods 47¹ having setting nuts 48¹ engaging the rib 49¹; and in the second-mentioned chain, shoes 51 engage on the outer edges 45 of the plates 44 of links 23, these shoes being spring-pressed at 52 into said engagement.

When the sewing through the forward pair 19¹ of holes has been completed as above described, the bars 58 are moved forwardly a sufficient distance to bring the rearward pair 19 of the same button's holes into registering position with the needle. Said bars are thus moved automatically by the following means:

A helically-threaded gear or worm 63 on the 35 sewing machine's shaft 4 (which operates the needle) meshes with a worm wheel 64 on shaft 65 carrying a cam wheel 66 with a cam groove 67 in its outer side. One of the arms 55 is pivotally connected (for adjustment as hereinafter explained) with one arm 68 of a bell crank lever (fulcrumed on a pivot rod 111) whose other arm 70 has a roll 69 traveling in said cam groove 67.

When the sewing through the forward pair 19¹ of the button's holes is going on, the wheel 66 is 45 in such turned position that the roll 69 is in the low half 72 of groove 67 thus holding the arms 55, and parallel bars 58 in their rearward position so that the needle passes through the forward pair 19¹ of the button's holes; but when the wheel 66 turns to the position wherein the roll passes into the high half 71 of said groove, the bars 58 are moved forwardly so that the needle may now pass through the button's rearward pair of holes 19. The machine's sewing operation is suspended 55 while the chains 20 are being travelled by their wheels to present a new button to the needle.

The machine's shaft 4 has a cam wheel 77 (best seen in Figures 20 and 21) with a side cam 78, a diametrically opposite peripheral cam 79, 60 and a notch 83 in its periphery. This wheel and the shaft 4 are held from turning (and the machine's sewing operation is thus held suspended) by a detent 81 urged into this notch by a spring 87 pressing the detent endwise in its bearing in a block 83 carried by a rock shaft 84. This block has an arm 88 with a lateral pin 89 (see Figure 5) engaging in a slot 90 in arm 91 of a bell crank lever whose other arm 92 has a roll 93 traveling on the cam periphery 94 of a wheel 95 on the same shaft 65 which carries said cam wheel 66. When permitted so to do, a spring 82 surrounding the slidably mounted rod 85 (pivoted at 86 on the block 83) urges the same outwardly (toward the left-hand side of Figure 5). 75

In the position of the parts shown in Figures 1 and 5, the arm 74 of pedal 33 has been pressed down to advance a button to the needle and the sewing of the button has been half finished (that is, the sewing through its forward pair of holes 19¹ has been finished) while the roll 93 has been traveling in the low half 72 of cam wheel 66 and is now about to pass into the high half 71 of said cam to shift the parallel bars 56 forwardly and move the same button to a position to be sewed through its rearward pair of holes 19. The cam wheels 66 and 95 thus make one complete revolution for the sewing of any button—half a revolution for sewing through its forward holes 19¹ and the other half revolution for sewing through its rearward holes 19—during which complete single revolution the machine's shaft 4 and the cam wheel 77 thereon revolve many times in the sewing operation.

The sewing operation having been suspended and the detent 81 being in the notch 80 of cam wheel 77, the sewing operation is resumed by pressing arm 101 of pedal 33 down which action causes the hook upper end of lever catch 98 (engaging the squared portion of pin 89) to move arm 100 downwardly and thus swing block 83 inwardly (toward the right-hand side of Figure 5) thus moving the detent sidewise out of notch 80 (against the pressure of spring 82) to permit the shaft 4 to revolve and resume the sewing operation; and the same action caused by pressing pedal arm 101 also turns bell crank 91, 92 so as to move roll 93 out of the short low portion 97 of the cam periphery 94 of wheel 95, said roll having been in said low portion while the sewing operation was suspended. During the complete sewing operation while the button is being sewed through both pairs of its holes, this roll travels on the extended high portion 96 of the cam periphery 94 of wheel 95.

When the roll 93 begins to drop into the short low portion 97, the detent's left-hand side (Figure 5) is pressed by spring 82 on the flat side 109 of cam wheel 77, and then on its side cam 78 until its low point 106 is reached whereupon the detent's outer end 110 begins to ride up on this wheel's peripheral cam 79 (Figures 20, 21). By this time the cam wheel 77 has quickly made one revolution and cam wheel 95 has slowly made a sufficient part of one revolution to carry its low portion 97 away from roll 93 so that this roll may now ride (pedal arm 101 having been released) on the extended high portion 96 of wheel 95 whereby the detent is held from engaging in said notch until another cycle of the machine's operation for sewing another button is initiated by pressing the pedal arm 74 downwardly to advance said other button to the needle. When the bar 75 is slid by pedal arm 101 down far enough, the arm 102 of the catch lever 99 strikes the adjustable threaded stop 104 and turns the catch lever to its position seen in solid lines in Figure 5, thus releasing the pin 89, and when pedal arm 101 is released the catch lever is raised to position ready to again engage pin 89, and in the meantime roll 93 has passed beyond low part 97 of cam 94 to hold the detent in the position seen in Figure 5.

The belt 7 is shifted from the driving pulley 5 to the loose pulley 6 on the machine's shaft 4, when the sewing operation is to be suspended and back again when it is to be resumed, by the belt-engaging arm 103 on the rock shaft 64 (on which the block 83 is mounted) when said block is swung as hereinbefore explained.

The needle's carrying bar 9 is oscillated side-

wise of the machine to sew alternately through the holes of either pair 19¹ or 19 by the following means: The cam wheel 66 has on its inner side a cam groove 113 in which travels a roll 114 on the arm 115 carried by a sleeve 116 turnable about the pivot rod 111 and in a bearing 117 in the machine's frame, as shown in Figure 24. The needle's bar 9 reciprocates vertically in a bearing member 118 on one arm 119 of a bell crank lever fulcrumed at 120 (see Figure 22) the other arm 121 of this lever being connected by a flexible joint 122 to a rod 123 which is connected by a flexible joint 124 to a lateral extension 125 of an arm 131 pivoted at 132. This rod 123 is turnable in members of these flexible joints and is threaded in one of them or oppositely threaded in both as seen in Figure 5.

A spindle 139 is slidable in a longitudinal slot 136 in said arm 137 and in a corresponding slot 126 in arm 127 on sleeve 116 which operates the needle's oscillation. A hand nut 142 on the threaded outer end of this spindle may be turned to clamp its shoulder 141 on the inner side of arm 127 and thus adjust in the slots the position of the pivotal connection 140 between said arms (see Figure 25). A pointer arm 144 may be provided to indicate on the graduation 145 the position of said pivot.

By moving this spindle-pivot 140 in the slots, the length of the movement of rod 123 may be adjusted to accommodate buttons the holes of whose pairs thereof are spaced at different distances apart. By turning the wheel 66 to a position wherein the roll 114 is midway between any high point 171 and low point 172 of the cam groove 113 (as diagrammatically indicated in Figure 23) and thereupon turning the rod 123 to bring the arms 127, 137 to the parallel (vertical) position seen in Figure 5, the oscillation of the needle will be so adjusted that it will move equal distances from the line of feeding extending directly toward the needle and thus the buttons are fed along their center lines toward the needle.

The arms 55 and arm 68 are to be adjusted correspondingly with arms 127 and 137 and by similar means, as shown in Figures 1, 7 and particularly in Figures 16 and 17. The arm 55 has a longitudinally extending cross-sectionally T-shaped slot 146 in which is slidable a member 147 in which the spindle portion 148 of a block 149 is turnable at 150. The arm 68 has a corresponding longitudinal slot 151 in which is slidable the squared portion 152 of said block. This block is threaded for an adjusting screw 153 journaled on arm 68 which screw may be turned to adjust the pivotal connection 148 between said arms 55 and 68.

The slot 146 of arm 55 is open at its bottom 154 so that the block 149 may be moved downwardly (as indicated in dotted lines in Figure 7) out of this slot by the screw 153 when buttons having only one pair of holes are to be used on the machine. In this use of the machine, the arms 55 are held against movement by means of a latch pin 155 slidable in a bore 156 in a projection 157 of one of said arms and pressed by a spring 158 into a keeper socket 159 in a portion 160 of the machine's frame, as indicated in Figure 18. When the machine is to be used for sewing buttons having forward and rearward pairs of holes the arm 55 is released by drawing the latch pin out of said keeper socket and turning it so that its lateral lug 161 rests on the outer edge 162 of said projection 157.

The free end 128 of a strip 17 (after the buttons are detached therefrom) may at intervals be severed by shears comprising a fixed blade 129 and a movable blade 130 carried by arm 131 of a bell crank lever whose other arm 132 has a roll 133 traveling on the cam periphery 134 of a wheel 135 on shaft 65, as seen in Figures 1 and 5.

The parallel arms 58 are not only turnable on the pivot rod 57 but are slidable therealong (so that the chains 20 may yieldingly engage the buttons at their opposite edges) by a spring 163 secured thereto and to the opposite arms of a lever member 164 pivotally mounted at 165 having its opposite arms connected by links 166 to the arms 58 respectively at 167 (see Figure 2). These arms 58 are thus adapted for use with buttons of different diameters. Flexible joints are shown at 168, 169, 170 as well as at 122, 124. In some cases one of the chains 20 may be dispensed with and in place thereof the buttons may be guided at one edge along a suitable slide bearing 173 as shown in Figure 26.

The invention being intended to be pointed out in the claims, is not to be limited to or by details of construction of any particular embodiment thereof illustrated by the drawings or hereinbefore described.

I claim:

1. Mechanism for feeding buttons to operatively-registering positions with the needle of a sewing machine, comprising: an element having a movement toward the needle and carrying the buttons movably therealong spaced in the direction of said movement; means for alternately moving said element and for moving the buttons therealong into such positions respectively.

2. Mechanism for feeding buttons to operatively-registering positions with the needle of a sewing machine, comprising: an element having a movement toward the needle and carrying the buttons movably therealong spaced in the direction of said movement; means operable by said machine's driving means for moving said element to feed the buttons thereon to one such registering position; means for feeding the buttons along said element to another such registering position.

3. In combination with a sewing machine having a needle and driving means: mechanism for feeding buttons to operatively-registering positions with the needle of the sewing machine, comprising: an element having a movement toward the needle and carrying the buttons movably therealong spaced in the direction of said movement; means operable by said machine's driving means for moving said element to feed the buttons thereon to one such registering position; means operable during suspension of said machine's sewing operation for feeding the buttons along said element to another such registering position.

4. Mechanism for feeding buttons to operatively-registering positions with the needle of a sewing machine, comprising: an element having a movement toward the needle; connected links mounted on said element, movable along said element and engaging the buttons to feed the same by the traveling movement of the links to one such position, said element and the links therewith being movable to feed the buttons to another such position.

5. Mechanism for feeding buttons to operatively-registering positions with the needle of a sewing machine, comprising: an element having a movement toward the needle; sprocket wheels

mounted on said element; a chain carried by the wheels engaging the buttons; means for rotating the wheels to feed the buttons to one such position, said element and the chain therewith being movable to feed the buttons to another such position.

6. Mechanism for feeding buttons to operatively-registering positions with the needle of a sewing machine, comprising: an element extending toward the needle; laterally spaced pairs of sprocket wheels mounted on said element; chains carried by said pairs respectively engaging the buttons therebetween; means for rotating the wheels to travel the chains together for feeding the buttons.

7. Mechanism for feeding buttons to operatively-registering positions with the needle of a sewing machine, comprising: an element having a movement toward the needle; laterally spaced pairs of sprocket wheels mounted on said element; chains carried by said pairs respectively engaging the buttons therebetween; means for rotating the wheels to travel the chains together for feeding the buttons to one such position, said element and the chains therewith being movable to feed the buttons to another such position.

8. Mechanism for feeding buttons to operatively-registering positions with the needle of a sewing machine, comprising: a pair of arms relatively movable laterally; parallelly disposed chains mounted on the arms respectively, movable along the arms and having links engaging the buttons at their opposite edges to feed the same.

9. Mechanism for feeding buttons to operatively-registering positions with the needle of a sewing machine, comprising: a pair of arms laterally spring-pressed toward each other; parallelly disposed chains mounted on the arms respectively, movable along the arms and having links engaging the buttons at their opposite edges to feed the same.

10. Mechanism for feeding buttons to operatively-registering positions with the needle of a sewing machine having a vertically movable work-engaging pressure foot, comprising: an element mounted swingably in a vertical plane, connected with said foot, having a horizontal movement toward the needle and carrying the buttons movably along said element spaced in the direction of said movement; means for alternately moving said element toward the needle and for moving the buttons therealong into such positions respectively.

11. Mechanism for feeding buttons to operatively-registering positions with the needle of a sewing machine, including: a flexible elongated strip having a series of flexible tongues thrust through the buttons for detachably mounting the same on the strip; means for moving the strip and feeding the buttons; means in the path of the strip's movement engaging between the strip and the buttons and flexing said tongues to a position detaching the buttons from the strip.

12. Mechanism for feeding buttons to operatively-registering positions with the needle of a sewing machine, including: a flexible elongated strip having a series of flexible tongues engaging the buttons for detachably mounting the same on the strip; means for longitudinally moving the strip and feeding the buttons; means in the path of the strip's movement for detaching the buttons from the moving strip comprising

ing a wedge element having a toe engaging between the strip and the buttons and being so inclined from the direction of said movement as to thereby flex the strip from the buttons and the tongues from engagement therewith.

13. Mechanism for feeding buttons to operatively-registering positions with the needle of a sewing machine, including: a flexible elongated strip having a series of flexible tongues engaging the buttons for detachably mounting the same on the strip; means for longitudinally moving the strip and feeding the buttons; means in the path of the strip's movement for detaching the buttons from the moving strip comprising a wedge element having guides for the edges of the strip and a toe engaging between the strip and the buttons and being so inclined from the direction of said movement as to thereby flex the strip from the buttons and the tongues from engagement therewith.

14. A flexible elongated feeding strip for buttons having a series of struck-out tongues extending through holes of the buttons and bent into engagement therewith to detachably mount the same on the strip, said tongues being adapted to be bent reversely to detach the buttons from the strip.

15. Mechanism for feeding to operatively-registering positions with the needle of a sewing machine buttons having pairs of holes spaced in the direction of their feeding movement, comprising: an element having a movement toward the needle and carrying the buttons movably therealong in the direction of said movement; means for alternately moving the buttons successively along said element to a position wherein one pair of said holes is in registration with the needle and for moving said element from said position wherein said pair is in registration with the needle to a position wherein the other pair of holes is in registration with the needle.

16. Mechanism for feeding to operatively-registering positions with the needle of a sewing machine buttons having pairs of holes spaced in the direction of their feeding movement, comprising: an element having a movement toward the needle and carrying the buttons movably therealong in the direction of said movement; means for alternately moving the buttons successively along said element to a position wherein one pair of said holes is in registration with the needle and for moving said element from said position wherein said pair is in registration with the needle to a position wherein the other pair of holes is in registration with the needle; means for relatively adjusting the movement of said element and the movement of the buttons therealong.

17. In combination with a sewing machine having a needle and driving means: mechanism for feeding to operatively-registering positions with the needle of the sewing machine buttons having pairs of holes spaced in the direction of their feeding movement, comprising: an element having a movement toward the needle and carrying the buttons movably therealong in the direction of said movement; means for alternately moving the buttons successively along said element to a position wherein one pair of said holes is in registration with the needle and for moving said element from said position wherein said pair is in registration with the needle to a position wherein the other pair of holes is in registration with the needle; said element being mov-

able by cams operated by the driving means of said machine.

18. In combination with a sewing machine having a needle and driving means: mechanism for feeding to operatively-registering positions with the needle of the sewing machine buttons having pairs of holes spaced in the direction of their feeding movement, comprising: an element having a movement toward the needle and carrying the buttons movably therealong in the direction of said movement; means for alternately moving the buttons successively along said element to a position wherein one pair of said holes is in registration with the needle and for moving said element from said position wherein said pair is in registration with the needle to a position wherein the other pair of holes is in registration with the needle; means operated by said machine's driving means for holding its sewing operation suspended during the movement of the buttons along said element.

19. In combination with a sewing machine having a needle and a driving shaft with a belt-carrying pulley and a loose pulley thereon and a belt shifter, mechanism for feeding to operatively-registering positions with the machine's needle buttons having pairs of holes spaced in the direction of their feeding movement, comprising: an element having a movement toward the needle and carrying the buttons; means operated by said machine's driving means for moving said element from a position wherein one pair of its holes is in registration with the needle to a position wherein the other pair of its holes is in registration with the needle; and means controlled by said driving means for shifting the belt to the loose pulley.

20. In mechanism of the character described for moving an elongated strip carrying buttons toward a position wherein the buttons operatively register with the needle of a sewing machine; means engaging the buttons for thus moving the strip and for then feeding the buttons detached therefrom into such registration.

21. In combination with a sewing machine having a needle and driving means: mechanism of the character described for moving an elongated strip carrying buttons toward a position wherein the buttons operatively register with the needle of the sewing machine; means engaging the buttons for thus moving the strip and for then feeding the buttons detached therefrom into such registration; shearing means operable by the machine's driving means for severing the strip from which the buttons have been detached.

22. In combination with a sewing machine having a needle and driving means: mechanism for feeding to operatively-registering positions with the needle of the sewing machine buttons having pairs of holes spaced in the direction of their feeding movement, comprising: a swingable arm; an element pivotally mounted thereon, carrying the buttons and movable by the swinging of the arm toward the needle; cam means operated by the driving means of said machine for swinging the arm and moving said element from a position wherein one pair of said holes is in registration with the needle to another position wherein the other pair of holes is in registration with the needle.

23. In combination with a sewing machine having a needle and driving means: mechanism for feeding to operatively-registering positions with the needle of the sewing machine buttons

- having pairs of holes spaced in the direction of their feeding movement, comprising: an element movable by said machine's driving means from a position wherein one pair of its holes is in registration with the needle to a position wherein the other pair of its holes is in registration with the needle; means for moving the buttons successively along said element to the position wherein its first-mentioned pair of holes is in registration with the needle; means for operatively disconnecting the machine's driving means from said element so that said element remains stationary and the means for moving the buttons therealong is operable.

24. In combination with a sewing machine having a needle adjustably oscillated in a direction transverse to the hereinafter-mentioned line, mechanism for feeding to operatively-registering position with the needle buttons arranged on a fed strip and having a pair of holes spaced in said direction through which holes the needle passes alternately in its sewing operation, said mechanism comprising: means including said strip for feeding and guiding the buttons along a feeding line toward the needle; and means for adjusting the length of the needle's oscillating movement. 5 10
